HOLDER FOR DISPOSABLE DRINKING CUP

Reginald O. Hardie, Cranston, R.I., assignor to Nyman Mfg. Co., Providence, R.I., a corporation of Rhode Island

Filed Aug. 4, 1969, Ser. No. 18,527

Term of patent 14 years

Int. Cl. D7—01

U.S. Cl. D44—10

FIG. 1 is a side elevational view of a holder for a disposable drinking cup showing my new design;

FIG. 2 is a front elevational view;

FIG. 3 is a rear elevational view;

FIG. 4 is a bottom plan view thereof; and

FIG. 5 is a top plan view thereof.

I claim:

The ornamental design for a holder for disposable drinking cup, substantially as shown.
